UNITED STATES PATENT OFFICE.

HORACE EVERETT, OF PHILADELPHIA, PENNSYLVANIA.

DESIGN FOR BUCKETS.

Specification forming part of Design No. 5,925, dated June 11, 1872.

Specification describing a new and original Design for a Bucket or Pail, designed by H. EVERETT, of Philadelphia, county of Philadelphia, State of Pennsylvania.

The drawing is partly a side elevation and partly a sectional elevation of a bucket or pail constructed according to my improved design, which consists of a body slightly bulged out at the center A, and tapering each way to the ends, with a rib or hoop-shaped formation, B, about midway between the center and each end, forced outward from the body of the metal, by spinning or pressing, about as much as the thickness of a hoop, with sloping edges *a* joining them with the body of the bucket. A

cover, C, with a wide hoop, D, extending down to the upper hoop, fits on the top, the said hoop D being shaped to correspond with the taper of the upper part of the body.

The bucket thus designed has the appearance of a keg with both ends made fast, when the cover is on.

I claim as new and desire to secure by Letters Patent—

The design for buckets and pails, substantially as herein shown.

HORACE EVERETT.
